FOREIGN PATENT DOCUMENTS

JP 2004008349 1/2004

Primary Examiner — Cynthia Ramirez

Assistant Examiner — Michael A Maharajh

(74) Attorney, Agent, or Firm — Thomas P. O'Connell;
O'Connell Law Firm**CLAIM**

The new and ornamental design for a sleeve for exercise apparatus, as shown and described.

DESCRIPTION

FIG. 1 is a perspective view of a sleeve for exercise apparatus showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings are for the purpose of illustrating portions of the sleeve for exercise apparatus, which form no part of the claimed design.
